[57] CLAIM

The ornamental design for a sole protector, as shown
and described.

DESCRIPTION

FIG. 1 is a front elevational view of the sole protector
showing my new design;

FIG. 2 is a rear elevational view thereof;

FIG. 3 is a left side elevational view thereof;

FIG. 4 is a right side elevational view thereof;

FIG. 5 is a top plan view thereof showing a portion of
the toe covering stretch material cut away so as to
reveal attachment straps; and,

FIG. 6 is a bottom plan view thereof.

FIG. 1

FIG. 2

FIG. 3

FIG. 4

FIG. 5

FIG. 6
